UNITED STATES PATENT OFFICE.

JESSE WATSON ANDREWS AND HARRY L. EVANS, OF NEWPORT, RHODE ISLAND,
ASSIGNORS TO CARTONING MACHINERY CORPORATION, OF NEWARK, NEW
JERSEY, A CORPORATION OF NEW JERSEY.

CARTON-FILLING MACHINE.

Application filed February 19, 1921. Serial No. 446,420.

To all whom it may concern:

Be it known that we, JESSE WATSON ANDREWS and HARRY L. EVANS, citizens of the United States, residing at Newport, in the county of Newport and State of Rhode Island, have invented certain new and useful Improvements in Carton-Filling Machines; and we do hereby declare the following to be a full, clear, and exact description of the invention, such as will enable others skilled in the art to which it appertains to make and use the same; reference being had to the accompanying drawings, and to characters of reference marked thereon, which form a part of this specification.

The present invention relates, generally, to improvements in machines for automatically filling and closing cartons and similar goods containers; and the invention has for its principal object to provide an improved automatic machine for successively feeding, setting up or opening, and holding collapsed cartons, filling the same with goods, and then closing the side flaps and tucking in the end flaps to simultaneously close both ends of the cartons to retain the inserted goods therein, all in a rapid and assured manner, and while retaining the cartons in horizontally disposed position throughout the performance of said operations so that comparatively little bodily movement and shifting of the same is required, whereby the risk of tearing or mutilating the cartons is reduced to a minimum, and waste of carton material is consequently eliminated.

Another object of this invention is to provide in combination with the carton handling mechanism, a novel construction of means for inserting thereinto the goods to be enclosed therein, in a rapid manner and with a minimum risk of injury either to the said goods or to the cartons.

Another object of this invention is to provide a novel means for shaping or folding the end closing flaps preparatory to tucking the same into the carton ends, together with a positive and simple means for producing the tucking movements of said end flaps.

Other objects of the present invention, not at this time more particularly enumerated, will be clearly understood from the following detailed description of the same.

With the various objects of the invention

in view, the same consists, primarily, in the novel carton filling and closing machine hereinafter set forth; and, the invention consists, furthermore, in the novel arrangements and combinations of the various devices and parts, as well as in the details of the construction of the same, all of which will be hereinafter more fully described, and then finally embodied in the claims appended hereto.

The invention is clearly illustrated in the accompanying drawings, in which:

Figure 1 is a side elevation of the novel machine, embodying the principles of the present invention; Figure 2 is a horizontal section of the same, taken on line 2—2 in said Figure 1; Figure 3 is a detail transverse vertical section, taken on line 3—3 in Figure 2; Figure 4 is a detail vertical longitudinal section, taken on line 4—4 in Figure 2, and drawn on an enlarged scale; Figure 5 is a view similar to Figure 4, but illustrating further operated positions of the parts shown in said latter figure; Figure 6 is a detail transverse vertical section, taken on line 6—6 in Figure 2; Figure 7 is a detail view similar to that shown in Figure 6, and drawn on an enlarged scale, to illustrate an operation of the filling or charging plungers preliminary to the insertion of goods into a carton; Figure 8 is a view similar to that shown in Figure 7, but illustrating further advanced operative positions of the carton filling or charging plungers; Figure 9 is a detail longitudinal vertical section, taken on line 9—9 in Figure 2 and drawn on an enlarged scale; Figure 10 is a detail plan view of the receiving end of the carton closing means, drawn on an enlarged scale; Figure 11 is a plan view of the carton closing means, drawn on an enlarged scale, and illustrating diagrammatically the procedure of a carton therethrough to produce the closing and tucking of the carton end flaps; Figures 12, 13, 14, 15 and 16 are respectively transverse sections on lines 12—12, 13—13, 14—14, 15—15 and 16—16 in Figure 11, to show the progressive operations carried out in closing and tucking the carton end flaps; Figures 17 and 18, are views similar to that shown in Figure 16, the same illustrating progressive operative movements of rotary tucking members; Figure 19 is a detail horizontal sec-

tion taken on line 19—19 in said Figure 16; and Figure 20 is an enlarged plan view of a Geneva movement for producing the timed intermittent driving of a rotary conveyor or 5 turn-table for successively receiving, holding, and feeding the cartons to the filling and closing means.

Similar characters of reference are employed in all of the hereinabove described 10 views to indicate corresponding parts.

Referring now to the drawings, the reference character 1 indicates a suitably supported base plate or bed, upon which is in turn supported, by standards 2, a table 3, 15 which is spaced above said bed in horizontal parallel relation thereto. Journaled in bearings 4, fixed to said bed 1 beneath said table 3, is a driving shaft 5, which is driven by the chain 6 and sprocket 7, or any other device 20 sired power transmission means, from a suitable source of power. Journaled in bearings 8 provided in said standards 2, at one side of the machine, is a longitudinal lay shaft 9, which is driven by the driving shaft 5 25 through the gear wheels 10 and 11. Journaled in bracket bearings 12, at one end of the machine, is a transverse lay shaft 13, which is driven from the lay-shaft 9 by the bevel gears 14 and 15. Journaled in bearings 30 16 provided in said standards 2, at the opposite side of the machine, is a second longitudinal lay shaft 17, which is driven from said transverse lay shaft 13 by the bevel gears 18 and 19. Fixed in a suitable 35 location on said bed 1 is a foot-piece 20 in which is supported the lower end of a vertical column or shaft 21, the upper end of which extends through and above said table 3. Rotatably mounted upon the upper 40 end of said column 21, above said table 3, is a horizontally disposed rotary conveyer or turn-table 22. Rotatably mounted upon the said column 21, beneath the table 3, is the female member 23 of a Geneva movement, 45 the hub of which extends upwardly through said table 3 so that said turn-table 22 may be fixed thereto. The reference character 24 indicates a vertical shaft journaled to extend between said bed 1 and table 3, the same 50 being driven from said driving shaft 5 by the bevel gears 25 and 26. Fixed on said vertical shaft 24, and driven thereby, is the male member 27 of said Geneva movement. The said Geneva movement operates to produce 55 a desired intermittent and timed rotation of said turn-table 22.

Said turn-table 22 is provided with a plurality of openings 28 in its marginal portions adjacent to its periphery, the same being 60 equally spaced apart, and so positioned as to properly and successively align themselves with carton feeding or delivery means at one point and carton filling means at another point during the intermittent stop periods of the turn-table movement. Pivoted

at their inner ends within each opening 28 are vertically swinging gripping devices 29 provided at their free ends with upwardly projecting transverse gripping lugs 30.

Fixed on said turn-table in associated relation to each opening 28 and its gripping device 29 is an abutment block 31, which when said gripping devices are raised to operative positions determine or limit a space intermediate the same and said gripping 75 lugs 30 equal to the width of an expanded or opened carton. Supported upon said table 3, in proper associated relation to said turn-table 22, is a suitably supported magazine 80 32, adapted to contain a vertical stack of collapsed cartons C. Means are provided to successively feed the cartons C from the bottom of the stack thereof, and then deliver the same upon the turn-table 22 in proper relation to the gripping devices 29 85 thereof; said means being timed to deliver a carton, as the gripping devices are successively positioned or alined relative to the magazine by the intermittent rotation of the turn-table. Said carton delivery means 90

comprises a reciprocatory member 33 moving in guides 34, and actuated by a lever 35 pivoted upon the table 3, said lever 35 being oscillated through interconnecting means by an eccentric 36 mounted on said transverse lay 95 shaft 13. Connected with the free end of said reciprocatory member 33 is a plunger 37 adapted to engage and push outwardly from the magazine 32 the bottom carton of the stack, so that the same drops upon the 100 surface of the turn-table 22 across said gripping device 29 positioned to receive the same, and in front of the abutment block 31. The delivery and fall of the collapsed carton being thus accomplished, a continued 105 forward movement of the reciprocatory member 33 carries a positioning or pilot plate 38 (which is attached to said reciprocatory member 33 so as to extend below and parallel to the plunger 37) into engagement 110 with the collapsed carton, as it rests upon the surface of the turn-table 22, and slides the same up to and against the abutment block 31 to properly position and aline the carton relative to the gripping means; all of which 115 may be better understood by an inspection of Figures 2 and 4 of the drawings. Connected with said turn-table 22 in proper locational relation to each carton gripping means is a vertically movable stop-pin 39 which is 120 depressed by a spring 40 so that its upper end is normally withdrawn below or flush with the surface of said turn-table 22. When, however, a gripping means is carried by the movement of said turn-table into 125 alinement with the carton delivery means, the adjacent stop-pin 39 engages with its lower end a lift-cam 41 which is fixed upon the table 3 in the path of its movement, and as the same rides upon said lift-cam 41 the 130

turn-table 22 comes to a stop, thus leaving the upper end of said stop-pin 39 projected above the surface of the turn-table (see Figure 3). Mounted for movement in the 5 guides of a guide bracket 42, which is fixed to said table 3, is a flat clamp-blade 43 having at its forward end a sharpened nose 43' having a thin knife-edge periphery. Said clamp-blade 43 is so located relative to the 10 turn-table 22, that the same is longitudinally alined with the collapsed carton as delivered upon the turn-table and registered against the abutment-block 31. Said clamp-blade 43 is of a width corresponding generally to 15 the width of the interior of the carton C, when the latter is expanded or opened. Said clamp-blade is reciprocated in timed relation to the delivery of the collapsed carton upon the turn-table 22, so that, after the carton is 20 registered against the abutment-block 31, the clamp-blade moves forward so as to enter the interior of the collapsed carton at one end to thereby engage and hold the under-side of the latter down upon the surface of 25 the turn-table; the carton being stopped against longitudinal displacement during the entrance of the clamp-blade thereinto by the engagement of its opposite end with the upwardly projected stop-pin 39 above de- 30 scribed. In order to prevent crumpling of the flaps at the end of the carton abutting said stop-pin 39, or riding up of said flaps over the stop-pin, under the pressure of the entering clamp-blade, with consequent dan- 35 ger of displacement of the carton from proper position, or danger of possible permanent injury to said flaps, there is provided a resilient presser foot 44, in the form of a leaf-spring device, which is carried by a 40 lever 45 pivoted to the side of said guide-bracket 42. A timed oscillation of said lever, in advance of the entry of said clamp-blade 43 into said carton, is produced by the action of a cam 46, fixed on said lay shaft 45 9, upon an anti-friction roller 47 carried by the outer end of said lever 45, whereby the presser foot 44 is swung downward into holding engagement with the end of said carton abutting said stop-pin 39. A spring 50 actuated plunger 48, or other suitable means, maintains the roller 47 of the lever 45 in operative riding engagement upon said cam 46; all of said described parts, and their relation one to another, being clearly illustrated 55 in Figures 2 and 3 of the drawings. The means for producing the desired timed reciprocal movements of the clamp-blade 43, comprises a lever 49 pivoted on said bed 1, the upper free end of which is connected 60 through the link 50 with the rear end of said clamp-blade. The clamp-blade actuating oscillations of said lever 49 are produced by means of a connecting rod 51 having a bifurcated end riding on and guided by said 65 driving shaft 5, said connecting rod having a pin or roller 52 engaged in the cam groove 53 of a cam-wheel 54 fixed upon and rotated by said driving shaft 5.

Initially the gripping devices 29 occupy a downwardly swung or depressed inoperative position so that their gripping lugs 30 are downwardly withdrawn below the surface of the turn-table 22. The collapsed cartons are scored longitudinally to demarcate the longitudinal faces C' and C² and sides 70 C³ and C⁴ of the same, see Figures 4 and 5. As delivered by the delivery means, the collapsed carton rests upon the turn-table so that the sides C³ thereof in the plane of the lower or under face C' is positioned over 75 the downwardly withdrawn gripping lug 30. When the gripping device 29 is swung upwardly into operative position, the upward movement of the gripping lug 30 first engages and bends upwardly the side C³, 80 while the face C' is held clamped against the surface of the turn-table 22 by the clamp-blade 43, thereby raising upward or lifting the face C² and turning upward the side C⁴ against the abutment-block 31, thus 85 expanding the carton to its longitudinally open condition ready for the insertion and reception of the goods to be enclosed therein. When thus expanded to its open condition, the raised gripping device 29 causes 90 the carton to be gripped and held upon the turn-table surface, in such open condition, between the gripping lug 30 and the abutment-block 31 as shown in Figure 5. The timed operation of the gripping device 29, 95 to cause the said opening and gripping of the delivered carton, is produced by a vertically reciprocated lifting-block 55 guided in an opening or way 55' provided in said table 3. A lever 56 fulerumed upon and 100 extending beneath said table 3 has its inner end pivotally connected with the lower end of said lifting-block 55. The said lever 56 is oscillated at proper times by a cam 57 mounted on said lay shaft 9 to operatively 105 engage an anti-friction roller 58 on the outer end of said lever. The gripping device 29 is provided at its free end with an anti-friction or tracker roller 59 which is engaged by the lifting-block 55 as the latter 110 moves upward to swing the gripping device into operative position. The above described operations resulting in the delivery of a collapsed carton, the opening of the same, and the gripping of the same in supported relation to the turn-table 22, are all 115 timed to take place while the turn-table 22 is stationary, or dwelling immovable during a stop period of its intermittent rotary movement as caused by the described 120 Geneva movement transmission operating the same.

After the carton is delivered, opened, and gripped in supported relation to and upon the turn-table 22, the clamp-blade 43 is 125 130

4 withdrawn to initial position, the presser foot 44 is raised, and thereafter the turn-table 22 resumes its rotative movement, which carries away the open carton, and 5 alines the next or succeeding gripping device with the carton feeding and delivery mechanism ready to receive the next carton. Arranged beneath said turn-table 22 is a 10 segmental step or track-cam 60, which is fixed to said table 3, and which extends around from a point of beginning or receiving end 61 abutting said lifting-block 55 to a terminal point adjacent to the carton closing means, as will subsequently appear. 15 When the gripping-device 29 is lifted to normal operative position by the rising of the lifting block 55, its tracker-roller 59 is lifted by the lifting-block 55 to the level of the traction surface of said track-cam 60, so that as the turn-table 22 rotates, the tracker-roller 59 rides off of the lifting-block 55 and on to the track-cam 60, consequently so long as the tracker-roller is thus engaged by the track-cam the gripping-device 29 is maintained in raised and operative position while the turn-table carries the carton engaged on the same around to operative disposition relative to a carton-filling or charging means. 20

30 The reference character 62 indicates a platform which is supported by the standards 2 to extend horizontally above the table 3 in suitably spaced relation thereto. Pivotally connected to the under side of 35 said platform 62, so as to depend therefrom in front of said carton magazine 32, is a swinging arm 63 provided at its lower end with a combined guide and ironing member 64. Normally said arm 63 is swung to one 40 side to withdraw from a location in front of the magazine 32 said guide and ironing member 64. Prior to the movement of the turn-table 22, however, and after the delivered carton is opened and gripped, said 45 arm 63 is swung downwardly to carry the guide and ironing member 64 over the opened carton for the purpose of pressing the same firmly down upon the turn-table surface between the gripping lug 30 and the abutment-block 31, said member 64 also 50 serving to guide the carton beneath the bottom of the magazine 32 for passage under the same as the turn-table 22 begins its rotative movements (see Figure 5). The 55 means for producing a properly timed oscillation of said swinging arm 63, comprises a vertical lever 65 pivoted to said bed 1, the upper free end of which is connected through a link 66 with said arm 63 at a 60 suitable point intermediate the fulcrum and the free end of the latter. Said vertical lever 65 is oscillated by a connecting rod 67 pivoted thereto, the free end of which is provided with lateral roller projections 65 68 and 69, one of which is operatively en-

gaged by a pushing cam 70, and the other of which is operatively engaged by a retracting cam 71, said cams being fixed on and rotated by said lay shaft 17. 70

Connected with the lower end of the magazine 32 is a horizontal segmental guard plate 72, which extends over the marginal portions of the turn-table 22 to a point of delivery of the cartons to a carton closing means. Said guard plate 72 is suitably supported, in proper spaced relation to the turn-table, by a bracket member 73, or any other suitable means. As the turn-table rotates, the gripped and open cartons are carried beneath said guard plate 72, and are held 75 by the latter against accidental displacement from the gripping means, as the same are carried by the rotation of the turn-table toward the carton filling or charging mechanism. 80

85 Mounted upon said platform 62 is a hopper 74 with which is associated a rotatable agitator 75, driven by the chain 76 from a sprocket wheel 77 mounted upon said transverse lay shaft 13. The goods to be placed 90 within the cartons are deposited in said hopper 74. As illustrative of the use and operation of the machine we have chosen to show the same as adapted to fill or charge the cartons with a plurality of small pieces 95 78, such, for example, as candy coated chewing gum tablets, candy pieces, cough drops and similar goods, although it will be understood that with suitable modification of the hopper and goods delivery mechanism 100 78, many other kinds of goods or articles may be operated upon by the machine and inserted into the cartons handled by the same. Connected with the hopper 74 are a series of 105 downwardly inclined chutes 79 corresponding in number to the number of articles desired to be placed within the carton. The rotary agitator 75 operates to assure the filling of the chutes 79. These chutes 79 are provided with suitably disposed delivery 110 ends 80 leading down to a desired point above the turntable 22. The delivery ends 80 of the chutes are provided with suitable check and release devices 81, the timed operation of which through the link transmission 115 82 actuated by the cam 83 fixed on the transverse lay shaft 13, impels the properly timed release of one article from each chute for delivery to the carton filling devices. The delivery ends 80 of said chutes 79 terminate 120 upon a thin horizontal goods supporting plate 84 which extends over the surface of the turn-table 22. 125

130 By reason of the intermittent movement of the turn-table 22, the open carton, as gripped and held thereon by the gripping devices, are eventually brought to rest in properly alined relation to a carton filling or charging mechanism. The said carton filling or charging mechanism comprises a

transversely disposed guide bracket 85, in the guides of which is mounted a reciprocating gauge plunger 86. Said guide bracket 85 is fixed upon said table 3, and is so positioned adjacent and relative to the turn-table 22 that the gauge plunger 86 will be longitudinally alined with the open carton, when the latter is stopped in position ready to be filled, and so that forward or inward movement of said gauge plunger 86 will cause the same to enter through the outer end of the open carton whereby its free end may be passed through the latter to project beyond the inner end of the same. Fixed upon the opposite side of the table 3, adjacent and relative to the opposite side of said turn-table 22, and so as to be in transverse alinement with said guide-bracket 85 and its gauge plunger 86, is another guide bracket 87 in the guides of which is mounted a reciprocating slide-bar 88. The reference character 89 indicates a U-shaped collocating frame, the arms of which embrace, and are preferably pivotally connected with the inner end of said guide bracket 87, so that the free end of said frame 89 extends inwardly to occupy a position paralleling and in front of the discharge ends 80 of said goods delivery chutes 79. The outer side 90 of said collocating frame 89 rests upon or is closely adjacent to the surface of said goods supporting plate 84, thus serving as a stop against which the goods or pieces 78, as they are delivered from the chutes, are brought to rest and alined in front of the inner end of the carton, while the inner side of the collocating frame is upwardly spaced from the goods supporting plate 84 so that the pieces 78 may pass beneath the same to enter said collocating frame. Said inner side 91 is provided with laterally projecting guard lips 92, which border the discharge ends of the chutes and serve to guide the pieces 78 as they pass under said inner side 91 of the collocating frame. Associated with said collocating frame 89 intermediate its sides, is a longitudinally disposed centrally positioned guard bar 93 which is spaced upwardly from the goods supporting plate 84 so that the pieces lie beneath the same when received within the collocating frame. Said guard bar 93 serves to prevent the pieces 78 from yielding upwardly with consequent displacement from the train thereof when subjected to the pressure incident to their impulsion into the carton. The end of the collocating frame 89 is provided with a lip 94 beneath which the upper closing flap of the inner end of the carton is disposed, when the latter is stopped in position to receive the pieces 78. The reference character 95 indicates a charging plunger having at its rear end an upwardly extending portion 96 provided with an opening 97 which straddles or receives said guard bar 93; connected by said portion 96 with said charging plunger 95, and upwardly offset relative thereto, is a rearwardly extending tail-piece 98, which is pivotally connected with said slide-bar 88. Prior to the operation of the carton filling mechanism, the release devices 81 release one piece 78 from each chute 80, so that the required number of pieces enter the collocating frame 89 in alined side by side relation in front of the charging plunger 95. The timed actuation of the gauge plunger 86 and charging plunger 95 is such that the same mutually cooperate to bunch and insert the pieces 78 into the carton disposed to receive the same. In operation, a forward movement is imparted to the gauge plunger 86 whereby the same is thrust endwise through the carton, with its forward end projecting slightly outward from the inner end of said carton, (the parts occupying the positions indicated in Figure 6). The actuation of said gauge plunger is such that the same remains stationary in said inwardly thrust position while the initiative forward movement of the charging plunger 95 takes place. The initiative forward movement of the charging plunger 95 causes the same to engage the train of pieces 78 and to thrust the same together against the backing afforded by the stationary gauge plunger 86, to thereby first close up or bunch the pieces 78 together in close side by side contact one with another (as illustrated by Figure 7 of the drawings). Upon completion of the initiative bunching movement of said charging plunger 95, the gauge plunger 86 is actuated to produce a retractive or withdrawing movement of the same which is synchronized with the continued forward movement of said charging plunger 95, whereby the bunched pieces 78 are advanced toward the inner open end of the carton to pass therethrough and to thereupon enter the interior of the carton so as to be properly stowed within the same, (the position of the respective plungers at the end of this charging movement thereof being illustrated more particularly in Figure 8). The pieces 78 being thus inserted within the carton, the gauge plunger 86 continues its withdrawing or retractive movement until the same is returned to normal initial position, and the charging plunger 95 is at the same time withdrawn or retracted to its normal position ready for the next operation. The means for producing the above-described timed actuation of the gauge plunger 86, comprises an upwardly extending lever 99 which is pivotally connected with said bed 1, and the upper free end of which is pivotally interconnected with said gauge plunger 86 by a link 100. Journalized in bearings 101 supported by said bed 1 is a shaft 102, which is rotated from said driving shaft 5 through the intermeshed bevel gears 25, 26 and 103. 130

6
 Fixed upon and rotated by said shaft 102 is a gauge plunger actuating cam wheel 104 having a properly shaped cam groove 105 in its face. Connected with said lever 99, 5 intermediate its free end and its fulcrum, is a connecting rod 106 having a bifurcated end 107 which straddles said shaft 102 so as to guide the reciprocatory movements of said connecting-rod 106, said bifurcated end 107 10 having a roller projection 108 entered in said cam groove 105, whereby the desired timed motion is imparted to said connecting rod. The means for producing the above-described 15 timed actuation of the charging plunger 95, comprises an upwardly extending lever 109 which is pivotally connected with said bed 1, and the upper free end of which is pivotally interconnected with said slide-bar 88, operating said charging plunger, by means of a link 110. Fixed upon and 20 rotated by said shaft 102 is a charging plunger actuating cam wheel 111 having a properly shaped cam groove 112 in its face. Connected with said lever 109, intermediate 25 its free end and its fulcrum, is a connecting rod 113 having a bifurcated end 114 which straddles said shaft 102 so as to guide the reciprocatory movements of said connecting rod 113, said bifurcated end 114 30 having a roller projection 115 entered in said cam groove 112, whereby the desired timed motion is imparted to said connecting rod 113. The plunger actuating means thus described is most clearly illustrated in Figures 35 1, 2 and 6 of the accompanying drawings.

Upon completion of the charging operations, as above described, whereby the desired contents are deposited within the carton, the latter is ready to be closed, and to 40 this end means are provided to remove the filled carton from the turn-table, and then propel the same through the carton flap closing and tucking means, which is so located that its receiving end is conveniently 45 adjacent to that point of the turn-table 22 where the cartons are stopped subject to the charging operations, and so that a simple direct movement quickly slides the filled carton to the closing mechanism without danger of disturbing or dislodging the contents 50 placed therein. The first step incident to the transfer of the filled carton to the closing mechanism is to release the carton gripping means of the turn-table 22 from operative holding engagement with said filled carton. 55 When the turn-table 22 stops its rotative movement to dispose a carton in goods receiving position, the tracker roller 59 of the gripping device 29 rides off the terminal end 60 of said track cam 60 on to a normally raised drop block 116, which is vertically movable through an opening 117 in said table 3, and which is positioned adjacent to the terminal end of said track cam 60 with its upper 65 end flush with the level of said track cam.

The said drop block 116 remains in normal raised position during the time the carton is being charged, so that the gripping lug 30 of the gripping device 29 is retained in operative holding engagement with the carton 70 during the charging operations. Upon completion of the carton charging operations, however, the said drop block 116 is subjected to a timed actuation which lowers or drops the same, thereby permitting the gripping device 29 to swing downward to withdraw said gripping lug 30 downwardly and clear up the turn-table surface, whereupon the filled carton may be engaged and bodily moved laterally to slide the same off the 80 turn-table surface and into operative relation to the closing mechanism (see Figure 9). The means for producing the desired timed operation of said drop block 116 comprises a lever 118 pivoted to the under side of 85 said table 3, and to the inner end of which is attached said drop block, while the outer end of said lever is downwardly off-set and provided with a roller projection 119 which operatively engages the underside of an actuating cam 120 fixed on and rotated by said lay shaft 17. A pull spring 121 interconnected between the inner end of said lever 118 and the bed 1 serves to maintain the lever in operative engagement with said actuating 90 cam 120. In order to assure the downward swinging movement of the gripping device 29, when released by the dropping of said drop-block 116, so that any tendency of its gripping lug 30 to cling to holding relation 95 to said carton is positively overcome, there is provided upon the rear underside of each gripping device 29 a downwardly off-set rearwardly projecting tripping lug 122, the free end of which projects rearwardly beyond the fulcrum of the gripping device. Vertically movable in an opening 123 provided in said table 3 is a trip-pin 124, which occupies a normally downwardly withdrawn 100 position beneath the free end of said tripping lug 122. Pivoted to the under side of said table 3 is a trip lever 125, to one end of which is connected the lower end of said trip-pin 124, while the opposite end is engaged in an eye or opening 126 in the inner end of 105 said drop block actuating lever 118. When said drop-block actuating lever is upwardly swung to hold said drop-block in normal position, the trip lever 125 is oscillated to hold the trip-pin 124 downwardly withdrawn, 110 whereas, when the drop-block actuating lever is downwardly swung to drop said drop-block, the trip lever 125 is simultaneously 115 oscillated to raise said trip-pin 124, which in turn pushes upwardly on said tripping lug 122 to positively actuate a downward swinging movement of said gripping device 29, as will be clearly evident from an inspection of Figure 9 of the drawings. The 120 filled carton being released from engagement 125

130

with the gripping device is now ready to be transferred to the closing mechanism.

Each carton C is provided at opposite ends of its side C³ with side flaps C⁵ and at opposite ends of its side C⁴ with similar side flaps C⁶, while the bottom or under face C' is provided at one end with an end flap C⁷ having at its extremity a tuck tongue C⁸, and the top or upper face C² is provided at the opposite end with an end flap C⁹ having at its extremity a tuck tongue C¹⁰.

The carton closing mechanism is disposed to extend longitudinally outward from the periphery of the turn-table 22 in alignment with the position of the carton as held by the turn-table for the filling or charging operations, so that as the carton is slid sideways off the turn-table it will enter the said carton closing mechanism. Said carton closing mechanism consists of a pair of longitudinally parallel supporting bars 127, each carrying an inwardly projecting longitudinal slideway bar 128 for supporting the cartons as they are moved sideways between the flap closing means. Suitably disposed inner bearings 129 and outer bearings 130 are provided adjacent to the respective ends of and beneath the slideway provided by the bars 128. Journaled in the inner bearings 129 is a transverse shaft 131 upon which is fixed a driving sprocket 132. Said shaft 131 extends toward said lay shaft 9, and is driven thereby through the bevel gears 133 and 134. Journaled in said outer bearings 130 is the supporting shaft 135 of an idler sprocket 136. Running over said sprockets 132 and 136 is a conveyor chain 137 having, at properly spaced intervals, impelling pieces 138 which ride between said slideway bars 128 so as to engage and propel the cartons through the closing mechanism. Supported in connection with said slideway bars 128, at the receiving end of the closing mechanism are flap closing and tucking devices which will be subsequently more fully described. Associated with the carton closing mechanism, is a means for transferring the filled carton from the turn-table 22 into the receiving end of said closing mechanism for movement through the latter. The transferring means comprises a transfer rake 139 provided with a lever arm or tail-piece 140 extending forwardly from the outer side thereof. The forward free end of said arm or tail-piece 140 is pivotally connected with the upper end of an oscillatable lever member 141 which is pivotally connected with said bed 1 to project upwardly therefrom. The means for oscillating said lever member 141 to produce a timed operation of said transfer rake 139 comprises an eccentric 142 mounted upon and operated by said transverse lay shaft 13, and interconnected with said lever member 141 by a connecting rod 143. Mounted upon a supporting bracket

144, at one side of said carton closing mechanism, is a fixed guide-block 145 provided with a guide cam-groove 146. Cooperating with said cam-groove is a pivoted lift-cam 147. Rigidly connected with the tail-piece 140 of said transfer rake 139 is a guide-arm 148 which extends rearwardly toward said guide-block 145, and which is provided at its free end with a roller projection 149 which enters and rides in said guide cam-groove 146 of said guide-block 145. To move the transfer rake 139 into operative position relative to the filled carton, for the purpose of moving the latter off the turn-table 22 and into the carton closing mechanism, it is necessary to lift or swing the transfer rake upward to pass the same rearwardly over the carton and down behind the same.

This motion is accomplished as follows:— When the rearward oscillation of the lever member 141 moves rearwardly the transfer rake 139, the roller projection 149 of the guide-arm 148 is carried into engagement with the lift-cam 147, which causes the same to ride upwardly thereon through the upper portion of the guide cam-groove 146 as the parts move rearward, with the result that the guide-arm 148 is swung upward imparting a like upward movement to said transfer-rake 139 so that the same is raised above the carton as it passes over the latter. As the limit of rearward movement is reached, the roller projection drops downward at the rear end of said guide cam-groove to the lower level of the latter, so that the transfer rake drops behind the filled carton in position to engage the same. Upon forward movement of the transfer rake, the roller projection 149 of the guide-arm 148 passes forwardly through the lower level of the guide-cam groove, and in passing beneath the lift-cam 147 swings the same upwardly on its pivot whereby it is caused to yield to such forward movement, dropping back to operative position upon the passing of the roller projection thereby, and thus being ready to exercise its lifting function at each repetition of the reciprocatory movement of the transfer-rake. The transfer-rake 139 being positioned to engage the filled carton, the forward movement of the transfer rake slides the carton forwardly off the turn-table 22, causing the same to enter the carton closing mechanism. The said transfer-rake is provided on each side with forwardly projecting lugs 150 which serve as side flap closers. As the transfer-rake moves into engagement with the filled carton, the said side flap closers 150 engage the side flaps C⁵ and turn the same inwardly from the plane of the side C³ to extend at right angles to the latter and partially across the open ends of the carton, as shown in Figures 10 and 11.

Supported upon said slideway bars 128

to extend forwardly from the inner or receiving end of said carton closing mechanism, on each side thereof, are tuck tongue turning guides, the same comprising a pair 5 of guide bars 151 and 152, each having a convolved inner face. The respective guide bars 151 and 152 are associated together with their convolved faces opposed and spaced apart to provide a tortuous or twisted 10 guideway 153 of proper shape to receive and act upon the tuck tongues of the carton end flaps so as to bend the same over and inwardly as they pass through said guideways. The arrangement and positioning of said 15 pairs of guide bars 151 and 152 is such that one pair or set of said guide bars is disposed to act upon the end flap C⁷ and its tuck tongue C⁸ which spring from the under or bottom face C¹ of the carton, while the 20 other pair or set of said guide bars is disposed to act upon the end flap C⁹ and its tuck tongue C¹⁰ which spring from the upper or top face C² of the carton. The forward ends of the guide bars 151 are 25 cut away at their sides, as at 154, to provide side flap turning portions. As the transfer rake 139 moves the carton into position between the guide bars 151, the side flaps C⁶ are engaged and turned inwardly 30 from the plane of the side C⁴ to extend at right angles to the latter and partially across the open ends of the carton, as shown in Figure 11. As the filled carton enters into engagement with the closing mechanism, the end flaps C⁷ and C⁹ respectively 35 enter the guideways 153, and thereupon an impelling piece 138 of the conveyor mechanisms rides into engagement with the entered carton and propels the same forward, whereby the tuck-tongues C⁸ and C¹⁰ are 40 acted upon in the manner indicated in Figures 11 to 15 inclusive. Located at the outer ends of said pairs of guide bars 151 and 152 are rotary tucking devices, the same comprising tucker rolls 155 which are mounted 45 on vertical spindles 156 so as to rotate in a horizontal plane. Said spindles 156 are journaled in said supporting bars 127 and slideway bars 128 to extend downwardly 50 through an extension 157 of the table 3, and fixed upon the lower ends of said spindles are spur gears 158. Slidably supported between guides 159 fixed to the under side of said extension 157, so as to reciprocate therein, is a rack-plate 160 provided on its opposite sides with rack-members 161 which respectively mesh with said spur gears 158. A timed reciprocation of said rack-plate 160 operates to produce a properly synchronized operation of the tucker-rolls 155 55 upon the carton as the latter is propelled past the same. The timed reciprocation of said rack-plate 160 is produced by a lever-member 162, which is pivotally connected 60 with said bed 1 to extend upwardly there- 65 from, and the free end of which is interconnected with said rack-plate 160 by a link 163. Said lever-member 162 is oscillated by means of a cam-wheel 164 fixed upon and rotated by said transverse lay shaft 13, said cam-wheel operating a connecting rod 165 which is pivotally connected with said lever-member 162. The said tucker-rolls 155 are provided in their peripheries at their inner sides with a receiving groove 166 the sides 70 of which form a dihedral angle. Said receiving grooves communicate at their rearward ends with downwardly inclined tucking grooves 167 diminishing gradually in depth until merged with the outer periphery 75 of or circumference of the tucker-rolls. As the cartons are propelled out of the guideways 153, the end flaps C⁷ and C⁹ with their inwardly turned tuck-tongues are turned slightly downward, and the same ride into 80 said receiving grooves 166 of the tucker rolls, to occupy positions therein (as shown in Figure 16) ready for the tucking operations. Rotary motion is now imparted to the tucker rolls, so that the tucking grooves 85 167 are caused to ride against the end flaps and their inwardly turned tuck-tongues, whereby the diminishing depth and changing positions and shape of the said tucking grooves forces the end flaps into closed 90 position and at the same time causes the tuck tongues to enter the ends of the carton within the faces of the same. The rotation of the tucker rolls finally carries their smooth vertical faces 168 into which the 95 tucking grooves 167 merge, against the end flaps to complete the closing movement thereof. In order to provide for a final and complete endwise thrust against the closed carton so as to assure a complete closure of 100 the ends, and to overcome any tendency of the end flaps to spring open, one or both of the tucker rolls 155 may be provided on their smooth vertical faces 168 with a pinching or compression tip 169, which rides into 105 engagement with the adjacent end-flap to produce an additional inward thrust or compression of the same into its normal closed position with its tuck-tongue firmly thrust into tucked engagement within the carton 110 end. The above operations will be understood from an inspection of Figures 16, 17 and 18. Upon the completion of the end-flap closing and tucking operations the filled 115 carton is impelled away from the tucker-rolls and rides between the guard bars 170 to be finally ejected from the machine on to a table or other suitably arranged receiver (not shown). In order to prevent upward and outward displacement of the cartons, as 120 they are passed through the carton closing mechanism, there are provided the upper or top slideway bars 171, the inner margins of which overhang the passageway through 125 which the cartons move, so as to engage 130

the upper sides of the said cartons at their ends.

From the above description of the construction, arrangement and operation of the various groups of devices and their parts, the operation of the machine as a whole will be clearly understood without necessity for further recapitulation, except to say, that the operations are 10 successively carried out in a continuous manner, the various groups of devices being synchronized for proper correlation as will be clearly evident.

Having thus described the present invention, we claim:—

1. A machine of the kind described, comprising an intermittently rotatable turn-table, means for successively supplying collapsed cartons to said turn-table, means to 20 open and grip said cartons in retained relation upon said turn-table, the intermittent rotation of said turn-table successively stopping said cartons in position to be filled, means for supplying goods for insertion 25 within said cartons, means for inserting said goods into said cartons, means to close the open ends of said cartons, and means for successively transferring filled cartons from said turn-table to said end closing 30 means.

2. A machine of the kind described, comprising an intermittently rotatable turn-table, means for successively supplying collapsed cartons to said turn-table, means to 35 open and grip said cartons in retained relation upon said turn-table, means for temporarily clamping a collapsed carton on said turn-table subject to the operation of said opening and gripping means, the intermittent rotation of said turn-table successively stopping said cartons in position to be 40 filled, means for supplying goods for insertion within said cartons, means for inserting said goods into said cartons, means to close 45 the open ends of said cartons, and means for successively transferring filled cartons from said turn-table to said end closing means.

3. A machine of the kind described, comprising an intermittently rotatable turn-table, means for successively supplying collapsed cartons to said turn-table, means to open and grip said cartons in retained relation upon said turn-table, the intermittent rotation of said turn-table successively feeding 55 said cartons to and stopping the same in position to be filled, means for holding said gripping means in operative retaining relation to the cartons while the latter are carried to and stopped in filling position, 60 means for supplying goods for insertion within said cartons, means for inserting said goods into said cartons, means to close the open ends of said cartons, means for successively transferring filled cartons from

said turn-table to said end closing means, 65 and means to release said gripping means prior to the operation of said transferring means.

4. A machine of the kind described, comprising means to supply cartons; means to 70 open, hold and successively move said cartons into filling position; means for supplying goods for insertion within said cartons; a gauge-plunger; a charging-plunger opposed to said gauge-plunger; and actuating means for said respective plungers 75 adapted to first pass said gauge-plunger through a positioned carton from its outer end, then advance said charging plunger to engage the goods between the same and 80 said gauge plunger, and then retract the gauge-plunger in time with the continued advance of said charging-plunger whereby the goods are carried into and properly disposed within said carton.

5. A machine of the kind described, comprising means to supply cartons, means to open, hold and successively move said cartons into filling position, means for supplying goods for insertion within said cartons; 90 a gauge-plunger; a charging-plunger opposed to said gauge-plunger; and actuating means for said respective plungers adapted to first pass said gauge-plunger through a positioned carton from its outer end, then 95 advance said charging plunger to engage the goods between the same and said gauge plunger, and then retract the gauge-plunger in time with the continued advance of said charging-plunger whereby the goods are 100 carried into and properly disposed within said carton, means to close the open ends of said cartons, and means for successively transferring filled cartons to said end closing 105 means.

6. A machine of the kind described, comprising means to supply cartons; means to open, hold and successively move said cartons into filling position; means for supplying a plurality of articles for insertion 110 within a positioned carton; means for inserting said articles into said carton; means for collocating said articles relative to said carton and said inserting means; means to close the open ends of said cartons; and 115 means for successively transferring filled cartons to said end closing means.

7. A machine of the kind described, comprising an intermittently rotatable turn-table, means for successively supplying collapsed cartons to said turn-table, means to open and grip said cartons upon said turn-table, the intermittent rotation of said turn-table successively feeding said cartons to 120 and stopping the same in position to be filled, means for holding said gripping means in operation while said cartons are carried to and stopped in filling position,

means for supplying goods for insertion within said cartons, a gauge-plunger, a charging-plunger opposed to said gauge-plunger, actuating means for said respective plunger, means to close the open ends of said cartons, means for successively transferring filled cartons from said turn-table to said end-closing means, and means to release said gripping means prior to the operation of said transferring means.

8. A machine of the kind described, comprising an intermittently rotatable turn-table, means for successively supplying collapsed cartons to said turn-table, means to open and grip said cartons upon said turn-table, the intermittent rotation of said turn-table successively feeding said cartons to and stopping the same in position to be filled, means for holding said gripping means in operation while said cartons are carried to and stopped in filling position, means for supplying a plurality of articles for insertion within a positioned carton, means for inserting said articles into said carton, and means for collocating said articles relative to said carton and said inserting means, means to close the open ends of said cartons, means for successively transferring filled cartons from said turn-table to said end-closing means, and means to release said gripping means prior to the operation of said transferring means.

9. A machine of the kind described, comprising an intermittently rotatable turn-table, means for successively supplying collapsed cartons to said turn-table, means to open and grip said cartons upon said turn-table, means for temporarily clamping a collapsed carton on said turn-table subject to the operation of said opening and gripping means, the intermittent rotation of said turn-table successively feeding said cartons to and stopping the same in position to be filled, means for holding said gripping means in operation while said cartons are carried to and stopped in filling position, means for supplying a plurality of articles for insertion within a positioned carton, a gauge-plunger, a charging-plunger opposed to said gauge-plunger, means for collocating articles to be inserted in said cartons intermediate said charging-plunger and said gauge-plunger, actuating means for said respective plungers, means to close the open ends of said cartons, means for successively transferring filled cartons from said turn-table to said end-closing means, and means to release said gripping means prior to the operation of said transferring means.

10. A machine of the kind described, comprising an intermittently rotatable turn-table, means for successively supplying collapsed cartons to said turn-table, means to open and grip said cartons upon said turn-table, means for temporarily clamping a collapsed carton on said turn-table subject to the operation of said opening

and gripping means, the intermittent rotation of said turn-table successively feeding said cartons to and stopping the same in position to be filled, means for holding said gripping means in operation while said cartons are carried to and stopped in filling position, means for supplying a plurality of articles for insertion within a positioned carton, means for inserting said articles into said carton, and means for collocating said articles relative to said carton and said inserting means, means to close the open ends of said cartons, means for successively transferring filled cartons from said turn-table to said end-closing means, and means to release said gripping means prior to the operation of said transferring means.

11. A machine of the kind described, comprising an intermittently rotatable turn-table, means for successively supplying collapsed cartons to said turn-table, means to open and grip said cartons upon said turn-table, means for temporarily clamping a collapsed carton on said turn-table subject to the operation of said opening and gripping means, the intermittent rotation of said turn-table successively feeding said cartons to and stopping the same in position to be filled, means for holding said gripping means in operation while said cartons are carried to and stopped in filling position, means for supplying a plurality of articles for insertion within a positioned carton, a gauge-plunger, a charging-plunger opposed to said gauge-plunger, means for collocating articles to be inserted in said cartons intermediate said charging-plunger and said gauge-plunger, actuating means for said respective plungers, means to close the open ends of said cartons, means for successively transferring filled cartons from said turn-table to said end-closing means, and means to release said gripping means prior to the operation of said transferring means.

12. The combination with an intermittently rotatable turn-table of means for successively feeding collapsed cartons thereto, said turn-table having a series of carton opening and gripping means spaced around its marginal portions, each comprising an abutment against which a collapsed carton is deposited by said feeding means to be engaged thereby intermediate its ends, a vertically swinging gripping device pivotally attached to said turn-table to move upwardly in an opening therein, said gripping device having a lateral lug to expand and then grip the carton against said abutment, a reciprocating clamp-blade mounted adjacent to said turn-table, means for actuating said clamp-blade to insert the same into said collapsed carton to temporarily hold said carton on said table subject to the

operation of said gripping device, and means for imparting an upward operative movement to said gripping device.

13. The combination with an intermittently rotatable turn-table of means for successively feeding collapsed cartons thereto, said turn-table having a series of carton opening and gripping means spaced around its marginal portions, each comprising an abutment against which a collapsed carton is deposited by said feeding means to be engaged thereby intermediate its ends, a vertically swinging gripping device pivotally attached to said turn-table to move upwardly in an opening therein, said gripping device having a lateral lug to expand and then grip the carton against said abutment, a reciprocating clamp-blade mounted adjacent to said turn-table, means for actuating said clamp-blade to insert the same into said collapsed carton to temporarily hold said carton on said table subject to the operation of said gripping device, means holding said carton against longitudinal displacement under the operation of said clamp-blade, and means for moving said gripping device to operative position.

14. The combination with a carton filling mechanism and closing mechanism of an intermittently rotatable turn-table, means for successively feeding collapsed cartons thereto, a series of carton opening and gripping means spaced around the marginal portions of said turn-table for successive carton receiving presentation to said feeding means, and means for actuating said opening and gripping means to open and hold a carton subject to a filling operation, the intermittent rotation of said turn-table successively moving to and stopping in position to be filled the cartons engaged by said gripping means, a transferring means for moving a filled carton off said turn-table to said closing mechanism, and means for releasing said gripping means from the filled carton prior to the operation of said transferring means.

15. The combination with a carton filling mechanism and closing mechanism of an intermittently rotatable turn-table, means for successively feeding collapsed cartons thereto, a series of carton opening and gripping means spaced around the marginal portions of said turn-table for successive carton receiving presentation to said feeding means, means for actuating said opening and gripping means to open and hold a carton subject to a filling operation, a reciprocable clamp-blade mounted adjacent to said turn-table to enter a deposited collapsed carton to temporarily clamp the same subject to the operation of said opening and gripping means, and stop-means operable to hold the collapsed carton against longitudinal

displacement under the operation of said clamp blade, the intermittent rotation of said turn-table successively moving to and stopping in position to be filled the cartons engaged by said gripping means.

16. The combination with a carton filling mechanism and closing mechanism of an intermittently rotatable turn-table, means for successively feeding collapsed cartons thereto, a series of carton opening and gripping means spaced around the marginal portions of said turn-table for successive carton receiving presentation to said feeding means, means for actuating said opening and gripping means to open and hold a carton subject to a filling operation, a reciprocable clamp-blade mounted adjacent to said turn-table to enter a deposited collapsed carton to temporarily clamp the same subject to the operation of said opening and gripping means, stop-means operable to hold the collapsed carton against longitudinal displacement under the operation of said clamp blade, the intermittent rotation of said turn-table successively moving to and stopping in position to be filled the cartons engaged by said gripping means, a transferring means for moving a filled carton off said turn-table to said closing mechanism, and means for releasing said gripping means from the filled carton prior to the operation of said transferring means.

17. The combination with an intermittently rotatable turn-table of means for successively feeding collapsed cartons thereto, carton filling means associated with said turn-table, said turn-table having a series of carton opening and gripping means spaced around its marginal portions, each comprising an abutment against which a collapsed carton is deposited by said feeding means, a vertically swinging gripping device pivotally attached to said turn-table to move upwardly in an opening therein, said gripping device having a lateral lug to expand and then grip the carton against said abutment, means for temporarily holding the carton subject to the operation of said gripping device, means for raising said gripping device into operative position, the intermittent rotation of said turn-table successively moving said cartons to and stopping the same in operative relation to said filling means, a track-cam supported beneath said turn-table by which said gripping devices are held in operative position as the cartons are carried to said filling means, and means for releasing and dropping said gripping devices from said cartons after the latter are filled.

18. A machine of the kind described, comprising means to supply collapsed cartons having closing flaps and tuck-ends, means to open, hold and successively move said cartons with their flaps and tuck-ends open

- into filling position; means for supplying goods for insertion within a positioned carton; means for inserting goods into said carton; said inserting means comprising a 5 gauge-plunger adapted to be passed longitudinally through said carton, and a charging-plunger adapted to engage the goods against said gauge plunger and then insert the same into said carton as said gauge plunger is retracted from the carton.
- 10 19. A machine of the kind described, comprising means to supply collapsed cartons having closing flaps and tuck-ends; means to open, hold and successively move said 15 cartons with their flaps and tuck-ends open into filling position; means for supplying goods for insertion within a positioned carton; means for inserting goods into said carton; said inserting means comprising a 20 gauge-plunger adapted to be passed longitudinally through said carton, a charging-plunger adapted to engage the goods against said gauge-plunger and then insert the same into said carton as said gauge-plunger is retracted from the carton; means for closing 25 the carton flaps; means for closing and tucking the carton tuck-ends; and means for successively moving filled cartons into operative relation to said flap closing and said tuck-end closing and tucking means.
- 30 20. A machine of the kind described, comprising means to supply collapsed cartons having closing flaps and tuck-ends; means to open, hold and successively move said 35 cartons with their flaps and tuck-ends open into filling position; means for supplying a plurality of articles for insertion within a positioned carton; means for collocating a plurality of said articles in alinement with 40 an open end of said carton; means for inserting goods into said carton; said inserting means comprising a gauge-plunger adapted to be passed longitudinally through said carton to project from the receiving end 45 thereof, and a charging-plunger adapted to engage and bunch said collocated articles against said gauge-plunger and then insert the same into said carton as said gauge-plunger is retracted from the carton.
- 50 21. A machine of the kind described, comprising means to supply collapsed cartons having closing flaps and tuck-ends; means to open, hold and successively move said 55 cartons with their flaps and tuck-ends open into filling position; means for supplying a plurality of articles for insertion within a positioned carton; means for collocating a plurality of said articles in alinement with an open end of said carton; means for inserting goods into said carton; said inserting 60 means comprising a gauge-plunger adapted to be passed longitudinally through said carton to project from the receiving end thereof, a charging-plunger adapted to en-
- gage and bunch said collocated articles 65 against said gauge-plunger and then insert the same into said carton as said gauge-plunger is retracted from the carton; means for closing the carton flaps; means for closing and tucking the carton tuck-ends; and means for successively moving filled cartons into operative relation to said flap closing and said tuck-end closing and tucking means.
- 70 22. A machine of the kind described, comprising means to supply receptacles having flaps and a tucking portion at opposite ends; means to receive and hold said receptacles in horizontal position with their respective ends open and thereupon move the same successively into position to be filled; means for sliding goods endwise into a positioned receptacle; means for closing the flaps and tucking portions of the receptacles; means for transferring filled receptacles to said 80 closing means; and means for releasing said holding means prior to the operation of said transferring means.
- 85 23. A machine of the kind described, comprising means to supply receptacles having flaps and a tucking portion at opposite ends; means to receive and hold said receptacles in horizontal position with their respective ends open and thereupon move the same successively into position to be filled; means for sliding goods endwise into a positioned receptacle through one open end; means to enter the opposite open end of said receptacle and recede therefrom to gauge the position of the goods within the receptacle when 90 slid therein; means for closing the flaps and tucking portions of the receptacles; means for transferring filled receptacles to said closing means; and means for releasing said holding means prior to the operation of said 95 transferring means.
- 100 24. The combination with a slideway for receiving filled cartons having at their respective ends open end-flaps provided with tuck-tongues of means for propelling said 105 cartons through said slideway, means at the sides of said slideway provided with convolved guideways to receive said tuck-tongues to bend the same over and inwardly toward the open ends of said cartons, and 110 rotary means adjacent to the outer ends of said guideways to receive said end-flaps with their inwardly turned tuck-tongues, said rotary means operating to close said end-flaps and simultaneously enter said tuck-tongues within the ends of said cartons.
- 115 25. The combination with a slideway for receiving filled cartons having at their respective ends open end-flaps provided with tuck-tongues of means for propelling said 120 cartons through said slideway, means at the sides of said slideway provided with convolved guideways to receive said tuck-

- tongues to bend the same over and inwardly toward the open ends of said cartons, rotary tucker-rolls adjacent to the outer ends of said guideways, said tucker-rolls having 5 horizontal angular receiving grooves in their peripheries initially alined with said guideways to receive said end-flaps with their inwardly turned tuck-tongues, said tucker-rolls being further provided with helicoid 10 peripheral grooves extending from the inner ends of said receiving grooves and diminishing in depth until merged with the circumferences of said tucker-rolls, means for rotating said tucker-rolls when engaged with 70 said end-flaps and their tuck-tongues to close the former and simultaneously insert the latter within the ends of said cartons.
28. A machine of the kind described, comprising an intermittently rotatable turn-table, means for successively supplying collapsed cartons to said turn-table, means to open and grip said cartons in retained relation upon said turn-table, the intermittent rotation of said turn-table successively stopping 75 said cartons in position to be filled, means for supplying goods for insertion within said cartons, means for inserting said goods into said cartons, said cartons having at their ends open end-flaps provided with 80 tuck-tongues, a slideway adjacent to said turn-table, means for propelling said cartons through said slideway, means at the sides of said slideway provided with convolved 85 guideways to receive said tuck-tongues to 90 bend the same over and inwardly toward the ends of said cartons, rotary means adjacent to the outer ends of said guideways to receive said end-flaps with their inwardly turned tuck-tongues, said rotary means operating to close said end-flaps and simultaneously enter said tuck-tongues within the 95 ends of said cartons, and means for transferring filled cartons from said turn-table into said slideway. 100
29. A machine of the kind described, comprising an intermittently rotatable turn-table, means for successively supplying collapsed cartons to said turn-table, means to open and grip said cartons in retained relation upon said turn-table, the intermittent rotation of said turn-table successively stopping 105 said cartons in position to be filled, means for supplying goods for insertion within said cartons, means for inserting said goods into said cartons, said cartons having at their ends open end-flaps provided with 110 tuck-tongues, a slideway adjacent to said turn-table, means for propelling said cartons through said slideway, means at the sides of said slideway provided with convolved 115 guideways to receive said tuck-tongues to bend the same over and inwardly toward the ends of said cartons, rotary tucker-rolls adjacent to the outer ends of 120 said guideways, said tucker-rolls having horizontal angular receiving grooves in their peripheries initially alined with said guideways to receive said end-flaps with their inwardly turned tuck-tongues, said 125 tucker-rolls being further provided with helicoid peripheral grooves extending from the inner ends of said receiving grooves and diminishing in depth until merged with the outer circumferences of said tucker-rolls. 130
26. The combination with a slideway for receiving filled cartons having at their respective ends open side-flaps and end-flaps provided with tuck-tongues of means for propelling said cartons through said slideway, means for transferring said cartons from a filling point to said slideway, said transferring means having fingers for engaging and closing side-flaps at one side of said cartons, said slideway having side walls, the side-flaps at the opposite side of said 30 cartons being closed by contact with said side walls as the cartons enter therebetween, said side walls having convolved guideways to receive said tuck-tongues of said end-flaps to bend the same over and inwardly toward 35 the open ends of said cartons, and rotary means adjacent to the outer ends of said guideways to receive said end-flaps with their inwardly turned tuck-tongues, said rotary means operating to close said end-flaps and simultaneously insert said tuck-tongues within the ends of said cartons. 40
27. The combination with a slideway for receiving filled cartons having at their respective ends open side-flaps and end-flaps provided with tuck-tongues of means for propelling said cartons through said slideway, means for transferring said cartons from a filling point to said slideway, said transferring means having fingers for engaging and closing side-flaps at one side of said cartons, said slideway having side walls, the side-flaps at the opposite side of said cartons being closed by contact with said side walls as the cartons enter therebetween, 45 said side-walls having convolved guideways to receive said tuck-tongues of said end-flaps to bend the same over and inwardly toward the open ends of said cartons, rotary tucker-rolls adjacent to the outer ends of said guideways to receive said end-flaps with their inwardly turned tuck-tongues, said tucker-rolls being further provided with helicoid peripheral grooves extending from the inner ends of said receiving grooves and diminishing in depth until merged with the outer circumferences of said tucker-rolls. 50
26. The combination with a slideway for receiving filled cartons having at their respective ends open side-flaps and end-flaps provided with tuck-tongues of means for propelling said cartons through said slideway, means for transferring said cartons from a filling point to said slideway, said transferring means having fingers for engaging and closing side-flaps at one side of said cartons, said slideway having side walls, the side-flaps at the opposite side of said cartons being closed by contact with said side walls as the cartons enter therebetween, 55 said side-walls having convolved guideways to receive said tuck-tongues of said end-flaps to bend the same over and inwardly toward the open ends of said cartons, rotary tucker-rolls adjacent to the outer ends of said guideways to receive said end-flaps with their inwardly turned tuck-tongues, said tucker-rolls being further provided with helicoid peripheral grooves extending from the inner ends of said receiving grooves and diminishing in depth until merged with the outer circumferences of said tucker-rolls. 60
26. The combination with a slideway for receiving filled cartons having at their respective ends open side-flaps and end-flaps provided with tuck-tongues of means for propelling said cartons through said slideway, means for transferring said cartons from a filling point to said slideway, said transferring means having fingers for engaging and closing side-flaps at one side of said cartons, said slideway having side walls, the side-flaps at the opposite side of said cartons being closed by contact with said side walls as the cartons enter therebetween, 65 said side-walls having convolved guideways to receive said tuck-tongues of said end-flaps to bend the same over and inwardly toward the open ends of said cartons, rotary tucker-rolls adjacent to the outer ends of said guideways to receive said end-flaps with their inwardly turned tuck-tongues, said tucker-rolls being further provided with helicoid peripheral grooves extending from the inner ends of said receiving grooves and diminishing in depth until merged with the outer circumferences of said tucker-rolls. 70

rolls, means for rotating said tucker-rolls, and means for transferring filled cartons from said turn-table into said slideway.

30. A machine of the kind described, comprising an intermittently rotatable turn-table, means for successively supplying collapsed cartons to said turn-table, means to open and grip said cartons in retained relation upon said turn-table, the intermittent 5 rotation of said turn-table successively stopping said cartons in position to be filled, means for supplying goods for insertion within said cartons, means for inserting said goods into said cartons, said cartons 10 having at their ends open side-flaps and end-flaps provided with tuck-tongues, a slideway adjacent to said turn-table, means for propelling said cartons through said slideway, means at the sides of said slide- 15 way provided with convolved guideways to receive said tuck-tongues to bend the same over and inwardly toward the ends of said cartons, rotary means adjacent to the outer ends of said guideways to receive said end- 20 flaps with their inwardly turned tuck-tongues, said rotary means operating to close said end-flaps and simultaneously enter said tuck-tongues within the ends of said cartons, means for transferring filled 25 cartons from said turn-table into said slide- 30 way, and said transferring means having fingers for engaging and closing side-flaps at one side of said cartons, said side-flaps at the opposite side of said cartons being 35 closed by contact with the sides of said slideway when entering therebetween.

31. A machine of the kind described, comprising an intermittently rotatable turn-table, means for successively supplying col- 40 lapsed cartons to said turn-table, means to open and grip said cartons in retained relation upon said turn-table, the intermittent rotation of said turn-table successively stopping said cartons in position to be filled, 45 means for supplying goods for insertion within said cartons, means for inserting said goods into said cartons, said cartons having at their ends open side-flaps and end-flaps provided with tuck-tongues, a slideway ad- 50 jacent to said turn-table, means for propelling said cartons through said slideway, means at the sides of said slideway provided with convolved guideways to receive said tuck-tongues to bend the same over and in- 55 wardly toward the ends of said cartons, rotary tucker-rolls adjacent to the outer ends of said guideways, said tucker-rolls having horizontal angular receiving grooves in their peripheries initially alined with said guide- 60 ways to receive said end-flaps with their in- 65 wardly turned tuck-tongues, said tucker-rolls being further provided with helicoid peripheral grooves extending from the inner ends of said receiving grooves and diminish- ing in depth until merged with the circum-

ferences of said tucker-rolls, means for rotating said tucker-rolls when engaged with said end-flaps and their tuck-tongues to close the former and simultaneously insert the latter within the ends of said carton, means 70 for transferring filled cartons from said turn-table into said slideway, and said transferring means having fingers for engaging and closing side flaps at one side of said cartons, said side-flaps at the opposite side of 75 said cartons being closed by contact with the sides of said slideway when entering therein.

32. The combination with means to support an open carton having an end-flap provided with a tuck-tongue of means for bending said tuck-tongue over and inwardly toward the open end of said carton, and rotary means for engaging said end-flap together with the inwardly turned tuck-tongue, the turning of said rotary means operating to 80 close said end-flap and insert said tuck-tongue into the carton end.

33. The combination with means to support an open carton having an end-flap provided with a tuck-tongue of means for bending said tuck-tongue over and inwardly toward the open end of said carton, a rotary tucker-roll provided with a peripheral receiving groove to receive said end-flap with its inwardly turned tuck-tongue, said tucker- 90 roll being further provided with a helicoid peripheral groove extending from an end of said receiving groove and diminishing in depth until merged with the outer circumference of said tucker-roll, the turning of said 95 tucker-roll moving said diminishing helicoid groove in passing engagement with said end-flap and its tuck-tongue to close the former and insert the latter into the carton end.

34. The combination with means to support an open carton having an end-flap provided with a tuck-tongue of a means provided with a convolved way to receive said tuck-tongue for lateral movement there- 100 through operating to bend the same over and inwardly toward the open end of said carton, and rotary means for engaging said end-flap together with the inwardly turned tuck-tongue, the turning of said rotary means operating to close said end-flap and insert said 105 tuck-tongue into the carton end.

35. The combination with means to support an open carton having an end-flap provided with a tuck-tongue of a means provided with a convolved way to receive said tuck-tongue for lateral movement there- 110 through operating to bend the same over and inwardly toward the open end of said carton, a rotary tucker-roll provided with a peripheral receiving groove to receive said end-flap 115 with its inwardly turned tuck-tongue, said tucker-roll being further provided with a helicoid peripheral groove extending from an end of said receiving groove and dimin- 120 ishing in depth until merged with the outer 125 groove and diminishing in depth until merged with the outer 130

circumference of said tucker-roll, the turning of said tucker-roll moving said diminishing helicoid groove in passing engagement with said end-flap and its tuck-tongue 5 to close the former and insert the latter into the carton end.

In testimony that we claim the invention

set forth above we have hereunto set our hands this 12th day of February, 1921.

JESSE WATSON ANDREWS.

HARRY L. EVANS.
